SLIDE PROJECTOR

Richard J. Olson, Lima, and Frank A. Zagara, Rochester,
N.Y., assignors to Eastman Kodak Company, Rochester,
N.Y., a corporation of New Jersey

Filed Dec. 22, 1961, Ser. No. 68,027

Term of patent 14 years

(Cl. D61—1)

Fig. 5

Fig. 1

Fig. 4

FIG. 2

FIG. 3

FIG. 1 is a front perspective view of a slide projector showing our new design.

FIG. 2 is an elevational view of the side opposite that shown in FIG. 1;

FIG. 3 is a rear elevational view; and

FIGS. 4 and 5 are sectional details taken substantially on lines 4-4 and 5-5, respectively, of FIG. 3.

The bottom, not shown, is conventional.

The dominant features of our design are shown in solid lines in the drawing. The broken line showing of a slide aperture and slide tray mounting means is for illustrative purposes only.

We claim:

The ornamental design for a slide projector, as shown and described.
